(57) **CLAIM**

The ornamental design for a drawer slide jig, as shown and described.

DESCRIPTION

FIG. 1 is a perspective view of a drawer slide jig; FIG. 2 is a right side view of the drawer slide jig, wherein a left side view is substantially a mirror image of the right side view;

FIG. 3 is a front side view of the drawer slide jig; FIG. 4 is a back side view of the drawer slide jig; FIG. 5 is a top view of the drawer slide jig; and, FIG. 6 is a bottom view of the drawer slide jig.

The broken lines form no part of the claimed design.
